UNITED STATES PATENT OFFICE

105,820

DESIGN FOR A COAT

Abraham Botkin, Hyattsville, Md.

Application January 21, 1935, Serial No. 54,980

Term of patent 3½ years

To all whom it may concern:

Be it known that I, Abraham Botkin, a citizen of the United States, residing at Hyattsville, in the county of Prince Georges and State of Maryland, have invented a new, original, and ornamental Design for a Coat, of which the following is a specification, reference being had to the accompanying drawing, forming part thereof.

There is shown in the drawing, in

Figure 1, a front view of the coat in accordance with the present design, and

Figure 2, a rear view of such coat.

As shown in the drawing the coat is characterized by substantially straight sides 1 and 2

slightly flared at their lower portions and provided with cutaway portions 3 and 4. The pockets 17 and 18 present an angular appearance accentuated by wide and pointed lapels 5 and 6. The upper left-hand pocket 9 is angularly placed so that it substantially parallels the left lapel. The back of the coat is characterized by a straight line appearance of the vertical seams 12 and 14, horizontal seam 13 and pleats 15 and 16.

I claim:

The ornamental design for a coat, as shown and described.

ABRAHAM BOTKIN.
